(57) CLAIM

The ornamental design for a transparent tape dispenser, as shown and described.

DESCRIPTION

FIG. 1 is a left side view of the tape dispenser, showing my new design, with a head cover in a position for covering an application head;

FIG. 2 is a perspective view similar to FIG. 1;

FIG. 3 is a right side view thereof;

FIG. 4 is a perspective view similar to FIG. 3;

FIG. 5 is a top view thereof;

FIG. 6 is a view from below thereof;

FIG. 7 is a front view thereof;

FIG. 8 is a rear view thereof; and,

FIG. 9 is a right side perspective view thereof, with the head cover in a retracted position for exposing the application head.
